BUILDING ASSEMBLY

FIELD OF THE DISCLOSURE

The present disclosure relates generally to a building assembly.

BACKGROUND

Outdoor rooms are often constructed in outdoor spaces, and are usable for a variety of purposes such as to extend the usable living space of a home, to create a hobby or work area, for storage, etc. Many outdoor rooms have a complicated assembly, often including components that are heavy and/or bulky. Assembly of these rooms typically require multiple people and/or a professional builder, as well as many tools. Such complicated assemblies also lead to longer assembly times. The present disclosure is aimed at solving the problems identified above.

SUMMARY

In an embodiment, the building assembly comprises a floor frame, a roof spaced from said floor frame, and a plurality of walls extending between the floor frame and the roof and interconnected to define an interior and an exterior of the building assembly. At least one of the plurality of walls defines an opening. Each of the plurality of walls includes a plurality of panels with each panel defining a longitudinal axis and each panel having first and second ends, opposing top and bottom surfaces, an upper notch formed through the top surface and an opposing lower notch formed through the bottom surface with each of the upper and lower notches spaced inwardly along the longitudinal axis from at least one of the first and second ends. The plurality of panels includes first and second panels and the lower notch of the first panel mates with the upper notch of the second panel to form an interlocking joint between the first and second panels to interconnect the first and second panels and form adjacent interconnected walls of the plurality of walls of the building assembly.

In another embodiment, a building assembly comprises a floor frame having a plurality of floor panels each having first and second ends with the first end of one of the plurality of floor panels mating with the second end of an adjacent one of the plurality of floor panels to interconnect the plurality of floor panels, a plurality of posts each having first and second post ends with the first post end coupled to the floor frame. The at least one panel frame having first and second frame ends with the first frame end coupled to the floor frame and at least one window frame having an upper segment, a lower segment, and first and second side segments. The at least one window frame is interconnected to one of the posts such that the interconnected window frame, plurality of posts, panel frame, and floor frame collectively form a skeleton of the building assembly.

In yet another embodiment, a method of manufacturing a building assembly comprises the steps of: forming a floor; forming a roof spaced from the floor; forming a plurality of walls extending between the floor and the roof with each of the plurality of walls including a plurality of panels with each panel defining a longitudinal axis and each panel having first and second ends, opposing inner and outer sides, opposing top and bottom surfaces, an upper notch formed through the top surface and an opposing lower notch formed through the bottom surface with each of the upper and lower notches spaced inwardly along the longitudinal axis from at

2

least one of the first and second ends, a first mounting channel formed in the inner side extending along the longitudinal axis, and a second mounting channel formed in the outer side extending along the longitudinal axis, with the plurality of panels including first and second panels; mating the lower notch of the first panel with the upper notch of the second panel to form an interlocking joint between the first and second panels thereby interconnecting the first and second panels and forming adjacent interconnected walls of the plurality of walls, wherein the interconnected plurality of walls defines an interior and an exterior of the building assembly with at least one of the plurality of walls defining an opening; and coupling a door to at least one of the plurality of walls such that the door is movable between an open position in which the door is spaced from the opening and a closed position in which the door covers the opening.

BRIEF DESCRIPTION OF THE DRAWINGS

The advantages of the present disclosure will be readily appreciated as the same becomes better understood by reference to the following detailed description when considered in connection with the accompanying drawings. It is to be understood that the drawings are purely illustrative and are not necessarily drawn to scale.

FIG. 1 is a front perspective view of a building assembly according to an embodiment of the present disclosure.

FIG. 2 is a partially exploded view of a plurality of floor panels partially forming a floor frame of the building assembly.

FIG. 3 is an enlarged, partially exploded view of a portion of one of the floor panels of FIG. 2.

FIG. 4 is a partially exploded, perspective view of the plurality of floor panels interconnected to one another and a first floor joist partially forming the floor frame of the building assembly.

FIG. 5 is an enlarged view of a portion of adjacent floor panels interconnected to one another to form an interlocking joint.

FIG. 6 is an enlarged, partially exploded view of a portion of the first floor joist.

FIG. 7 is a partially exploded, perspective view of the plurality of interconnected floor panels, the first floor joist, and a plurality of second floor joists forming the floor frame of the building assembly.

FIG. 8 is a partially exploded, perspective view of the floor frame and a plurality of floor boards disposed on and supported by the floor frame.

FIG. 9 is a partially exploded, perspective view of a portion of a plurality of interconnected walls supported by the floor frame with each wall formed from a plurality of panels.

FIG. 10 is a cross-sectional view of one of the plurality of panels taken along line 10-10 in FIG. 9.

FIG. 11 is an enlarged view of a portion of the panel of FIG. 10.

FIG. 12 is a perspective view of a portion of one of the plurality of walls with an accessory removably attached to the wall.

FIG. 13 is a partially exploded, perspective view of a portion of one of the plurality of walls including caps for covering the respective ends of the panels of the wall.

FIG. 14 is an enlarged, perspective view of a portion of the building assembly showing interconnected base panels of adjacent walls.

FIG. 15 is an enlarged, partially exploded view of a portion of the floor frame and the base panels of adjacent walls of the building assembly.

FIG. 16 is a partially exploded, perspective view of the building assembly showing the floor frame, the plurality of walls, a plurality of panel frames, and a plurality of posts.

FIG. 17 is a perspective view of the building assembly showing the floor frame, the plurality of walls, a plurality of panel frames, and a plurality of posts.

FIG. 18 is an enlarged, partially exploded view of a portion of a panel frame for a side wall of the building assembly.

FIG. 19 is an enlarged, partially exploded view of a portion of a panel frame for a rear wall of the building assembly.

FIG. 20 is an enlarged, partially exploded view of a portion of one of the posts for the building assembly.

FIG. 21 is a partially exploded, perspective view of the building assembly including the floor frame, the plurality of walls, the plurality of panel frames, the plurality of posts, and a plurality of roof beams.

FIG. 22 is a partially exploded, perspective view of the building assembly including the floor frame, the plurality of walls, the plurality of panel frames, the plurality of posts, the plurality of roof beams, and a front window frame.

FIG. 23 is a partially exploded, perspective view of the building assembly including the floor frame, the plurality of walls, the plurality of panel frames, the plurality of posts, the plurality of roof beams, the front window frame, and a plurality of side window frames.

FIG. 23A is an enlarged exploded view of adjacent front and side window frames.

FIG. 24 is an enlarged, perspective view of a portion of the post interconnected to adjacent front and side window frames.

FIG. 25 is a semi-schematic, enlarged view of a portion of the post interconnected to adjacent front and first side walls of the building assembly with the post including a shelf.

FIG. 26 is a perspective view of the building assembly including the floor frame, the plurality of walls, the plurality of panel frames, the plurality of posts, the plurality of roof beams, the front window frame, the plurality of side window frames, and a roof joist.

FIG. 27 is an exploded, perspective view of a plurality of roof boards interconnected to one another.

FIG. 28 is an exploded, perspective view of a plurality of front roof boards interconnected to a plurality of rear roof boards.

FIG. 29 is an enlarged, perspective view of a portion of the interconnected front and rear roof boards.

FIG. 30 is an exploded, perspective view of the building assembly including the floor frame, the plurality of walls, the plurality of panel frames, the plurality of posts, the plurality of roof beams, the front window frame, the plurality of side window frames, the roof joint, and the roof board(s).

FIG. 31 is a perspective view of a skeleton of the building assembly according to another embodiment of the present disclosure.

DETAILED DESCRIPTION

Referring now to the figures, wherein like numerals indicate corresponding parts throughout the several views, embodiments of a building assembly 10 are shown throughout the figures and described in detail below. The building assembly 10 is a standalone, roofed structure adapted to

receive and/or hold objects, people, animals, etc. Alternatively, the building assembly 10 could be modified and/or adapted to be attached to a pre-existing building and may not, in this alternative example, be considered a standalone structure. Additionally, the building assembly 10 may be portable.

In an example, the building assembly 10 may be adapted for storing objects such as personal possessions, household items, furniture, yard or lawn equipment, office supplies and/or equipment, etc., and may be referred to as a storage shed, a garden shed, and/or the like. In another example, the building assembly 10 may be adapted for use by one or more persons as a workshop, a studio, an office, a hobby room, a garden or green room, a cabin or retreat, etc. In yet another example, the building assembly 10 may be adapted for providing shelter for animals, such as a shelter for dogs (i.e., a dog house), a shelter for chickens (i.e., a chicken coop), etc. Typically, the building assembly 10 is usable outdoors (such as outside of a permanent building or structure) and/or indoors (such as inside a permanent building or structure). It should be appreciated that the building assembly 10 can be adapted for use in any desired location and for any desirable purpose, including those purposes not specifically identified above.

The building assembly 10 may have any configuration. In the embodiments shown throughout the figures and described below, the building assembly 10 has a quadrilateral configuration (such as a square shape or a rectangular shape) in cross-section, and includes a front, a rear, a first side, and a second side. Alternatively, the building assembly 10 could have a cross-sectional configuration that is round, circular, oval, triangular, pentagonal, hexagonal, or any other geometry.

In the embodiments described below, the building assembly 10 is configured so that an end user or consumer can easily construct the building assembly 10 from a kit. The kit includes all of the components of the building assembly 10 available in a packaging available from a store. The individual components of the building assembly 10 are small enough so the user can easily place the packaging within the user's vehicle and/or the packaging can be easily delivered to the user by a delivery service or the like. In addition, many of the individual components of the building assembly 10, such as the panels 84 of the walls 16 of the building assembly 10, are formed from one or more lightweight materials, such as aluminum, vinyl, plastic, plywood, fiberboard, etc. The lightweight material(s) allows the user to easily handle the individual components at least during assembly of the building assembly 10. It should be appreciated that the building assembly 10 can alternatively have any size and/or include components formed from materials that are not necessarily lightweight. In this alternative embodiment, the building assembly 10 may or may not be available in the form of a kit.

Details of the building assembly 10 will now be described. As shown in FIG. 1, the building assembly 10 includes a floor frame 12, a roof 14 spaced from the floor frame 12, and a plurality of walls 16 extending between the floor frame 12 and the roof 14. The plurality of walls 16 are interconnected to define an exterior 20 of the building assembly 10. As shown, for example, in FIG. 9, the plurality of walls 16 are also interconnected to define an interior 18 of the building assembly 10. The interior 18 of the building assembly 10 refers to the inside of the building assembly 10 that is spaced or separated from an environment E external to or surrounding the building assembly 10. The exterior 20 of the building assembly 10 refers to the outside of the

building assembly 10 which is exposed to environment E surrounding the building assembly 10.

Details of the floor frame 12 and how the floor frame 12 is formed are described below with reference to FIGS. 1-7. As shown in FIG. 1, the floor frame 12 is adapted to be seated against and/or rest on the ground G of the environment E. The floor frame 12 is also adapted to support the plurality of walls 16 and the roof 14 of the building assembly 10. As shown in FIG. 8, the floor frame 12 supports at least one floor board 80 to form a floor 83 of the building assembly 10. Alternatively, the floor frame 12 could be modified to support just the walls 16 and the roof 14. In this alternative embodiment, the building assembly 10 does not have any floor boards 80, and the floor 83 of the building assembly 10 would be the ground G of the environment E. Alternative flooring for the building assembly 10 are also contemplated.

As shown at least in FIG. 2, the floor frame 12 comprises a plurality of floor panels 22 each defining a longitudinal axis A and having a length L_{FP} extending along the longitudinal axis A. Each floor panel 22 has first 24 and second 26 ends, opposing inner 28 and outer 30 sides, and opposing top 32 and bottom 34 surfaces. The inner side 28 of each of the floor panels 22 faces inwardly toward the inside of the building assembly 10 and forms part of the building interior 18. The outer side 30 of each of the floor panels 22 faces outwardly toward the environment E surrounding the building assembly 10 and forms part of the building exterior 20. As shown, for example, in FIG. 3, the inner 28 and outer 30 sides are spaced from one another to define a slot 36 between the sides 28, 30. In the illustrated embodiment, each floor panel 22 further includes at least one support rib 38 disposed within the slot 36 and extending along the longitudinal axis A.

The plurality of floor panels 22 are interconnected to form the floor frame 12. For example, one of the plurality of floor panels 22 mates with an adjacent one of the plurality of floor panels 22 to interconnect the plurality of floor panels 22 and form the floor frame 12. In the illustrated embodiment where the building assembly 10 has a quadrilateral configuration, the floor frame 12 includes four floor panels 22; a front floor panel 22_F, a rear floor panel 22_R spaced from the front floor panel 22_F, a first side floor panel 22_{S1} extending between the front floor panel 22_F and the rear floor panel 22_R, and a second side floor panel 22_{S2} extending between the front floor panel 22_F and the rear floor panel 22_R and spaced from the first side floor panel 22_{S1}. As best shown in FIG. 4, the front floor panel 22_F mates with the first side floor panel 22_{S1} and forms an interlocking joint 44 between the front 22_F and first side 22_{S1} floor panels, the first side floor panel 22_{S1} mates with the rear floor panel 22_R and forms an interlocking joint 44 between the first side 22_{S1} and rear 22_R floor panels, the rear floor panel 22_R mates with the second side floor panel 22_{S2} and forms an interlocking joint 44 between the rear 22_R and second side 22_{S2} floor panels, and the second side floor panel 22_{S2} mates with the front floor panel 22_F to interconnect second side 22_{S2} and front 22_F floor panels and forms an interlocking joint 44 between the second side 22_{S2} and front 22_F floor panels. The front 22_F, rear 22_R, first side 22_{S1}, and second side 22_{S2} floor panels are thereby interconnected to at least partially form the floor frame 12.

Referring again to FIG. 2, each of the first side 22_{S1} and second side 22_{S2} floor panels has an upper notch 40 formed through the top surface 32 spaced inwardly along the longitudinal axis A from each of the first 24 and second 26 ends. Each of the front 22_F and rear 22_R floor panels has a lower notch 42 formed through the bottom surface 34 spaced

inwardly along the longitudinal axis A from each of the first 24 and second 26 ends. The lower notch 42 about the first end 24 of the front floor panel 22_F mates with the upper notch 40 about the second end 26 of the first side floor panel 22_{S1} to form the interlocking joint 44 between the front 22_F and first side 22_{S1} floor panels. The upper notch 40 about the first end 24 of the first side floor panel 22_{S1} mates with the lower notch 42 about the second end 26 of the rear floor panel 22_R to form the interlocking joint 44 between the first side 22_{S1} and rear 22_R floor panels. The lower notch 42 about the first end 24 of the rear floor panel 22_R mates with the upper notch 40 about the second end 26 of the second side floor panel 22_{S2} to form the interlocking joint 44 between the rear 22_R and second side 22_{S2} floor panels. The upper notch 40 about the first end 24 of the second side floor panel 22_{S2} mates with the lower notch 42 about the second end 26 of the front floor panel 22_F to form the interlocking joint 44 between the second side 22_{S2} and front 22_F floor panels. In an embodiment, the configuration of the upper notches 40 of the floor panels 22 may be the same as the configuration of the upper notch(es) 106 of each of a plurality of panels 84 of each of the plurality of walls 16. The configuration of the lower notches 42 of the floor panels 22 may be similar to the configuration of the lower notch(es) 108 of each of the plurality of panels 84 of each of the plurality of walls 16; however, the floor panels 22 do not have a groove 120. Further details of the upper 106 and lower 108 notches of the plurality of panels 84 of the plurality of walls 16 are described below. In another embodiment, and as shown, the upper notches 40 of the floor panels 22 may have a first depth and the lower notches of the floor panels 22 may have a second depth larger than the first depth.

The bottom surface 34 of each floor panel 22 has a flat configuration extending at least partially along the length L_{FP} of the floor panel 22. The bottom surface 34 of the floor panel 22 is adapted to be in direct contact with the ground G of the environment E and adapted to be seated against and/or rest on the ground G. The top surface 32 of each of the floor panels 22 defines a tongue 46 extending outwardly in a direction transverse to the longitudinal axis A. The tongue 46 extends at least partially along the length L_{FP} . The tongue 46 is configured to mate with the groove 120 of a respective one of the plurality of panels 84 of the plurality of walls 16 to interconnect the respective one of the plurality of panels 84 with the floor panel 22. The configuration of the tongue 46 of the floor panel 22 is the same as the configuration of the tongue 118 of the panel 84, which is described below.

In an embodiment, each of the floor panels 22 (i.e., the front floor panel 22_F, the rear floor panel 22_R, the first side floor panel 22_{S1}, and the second side floor panel 22_{S2}) has first 48 and second 50 floor panel segments. Each of the first 48 and second 50 floor panel segments has a length L_{FPS} extending along the longitudinal axis A, and the lengths L_{FPS} of the segments 48, 50 may be the same or different. Additionally, and as best shown in FIG. 3, each of the first 48 and second 50 floor panel segments defines the slot 36, and one of the first 48 and second 50 floor panel segments has a tab 54. The tab 54 of the one of the first 48 and second 50 floor panel segments is disposed within the slot 36 of the other one of the first 48 and second 50 floor panel segments to interconnect said first 48 and second 50 floor panel segments to form the floor panel 22. In an embodiment, the one of the first 48 and second 50 floor panel segments has

a single tab **54**. Alternatively, the one of the first **48** and second **50** floor panel segments could have any number of tabs **54**.

The first floor panel segment **48** has the second end **26** of the floor panel **22** and a first segment end **56**, and the second floor panel segment **50** has the first end **24** of the floor panel **22** and a second segment end **58**. In the embodiment shown, the tab **54** extends from the from the second segment end **58** of the second floor panel segment **50** along the longitudinal axis A. The tab **54** may be secured to the second floor panel segment **50** about the second segment end **58** in any suitable fashion, such as with one or more fasteners **57**. The tab **54** extends from the second segment end **58** of the second floor panel segment **50** and into the slot **36** of the first floor panel segment **48**. The tab **54** is secured to the first floor panel segment **48** in any suitable fashion, such as with one or more fasteners **59**.

Each of the plurality of floor panels **22** further includes at least one bracket **60** attached or secured to the inner side **28**. Each of the first **22_{S1}** and second **22_{S2}** side floor panels has a bracket **60** attached or secured to the inner side **28**. This pair of brackets **60** is opposite one another and configured to receive and support a first floor joist **62**, as best shown in FIGS. 4, 7, and 8. The bracket **60** may be attached at any position along the length L_{IP} of the first side floor panel **22_{S1}**, and the other bracket **60** may be attached at a comparable or similar position along the length L_{FP} of second side floor panel **22_{S2}** such that the brackets **60** are opposite one another. In an embodiment, and as shown, the bracket **60** attached to the first **22_{S1}** and second **22_{S2}** floor panels has first **61** and second **63** bracket portions, with the first bracket portion **61** attached to the first floor panel segment **48** and the second bracket portion **63** attached to the second floor panel segment **50**. The first **61** and second **63** bracket portions come together to form a single bracket **60** having a U-shaped configuration in cross-section when the first **48** and second **50** floor panel segments are joined to one another.

Each of the front **22_F** and rear **22_R** floor panels has a plurality of brackets **60** attached or secured to the inner side **28**. In instances where a bracket **60** is positioned where the first **48** and second **50** floor panel segments are joined together, the bracket **60** may have the first **61** and second **63** bracket portions that are brought together to form a U-shaped bracket **60** in cross section when the panel segments **48, 50** are joined together as described above. Otherwise, the bracket **60** is a single piece having a U-shaped configuration in cross section. Each one of the plurality of brackets **60** of the front floor panel **22_F** has a respective one of a plurality of brackets **64** attached or secured to the first floor joist **62** such that the brackets **60, 64** of each pair are opposite one another.

As shown at least in FIG. 4, each one of the brackets **64** of the first floor joist **62** is a single piece having a U-shaped configuration in cross-section except where the bracket **64** is located where first **70** and second **72** joist segments are joined together. The first **70** and second **72** joist segments are described below. Additionally, each pair of respective brackets **60, 64** that are opposite one another are configured to receive and support a second floor joist **66**. The brackets **60, 64** may be attached or secured to the respective floor panels **22** and the first floor joist **62** by any suitable means, such as with one or more fasteners.

With reference to FIGS. 4 and 6, the floor frame **12** has the first floor joist **62** extending between the first **22_{S1}** and second **22_{S2}** floor panels. The first floor joist **62** is transverse to the first **22_{S1}** and second **22_{S2}** floor panels and extends

substantially parallel to the front **22_F** and rear **22_R** floor panels. The first floor joist **62** has first **65** and second **67** joist ends, with the first joist end **65** abutting and/or coupled to the first side floor panel **22_{S1}** and the second joist end **67** abutting and/or coupled to the second side floor panel **22_{S2}**. In an embodiment, the first joist **62** further has the first **70** and second **72** joist segments joined to one another to form the first joist **62**. The first joist segment **70** has the first joist end **65** and a first joist segment end **71**, and the second joist segment **72** has the second joist end **67** and a second joist segment end **73**. Each of the first **70** and second **72** joist segments defines a slot **68**. In an embodiment, the second joist segment **72** has at least one tab **74** extending from the second joist segment end **73**. The tab **74** of the second joist segment **72** is disposed within the slot **68** of the first joist segment **70** and attached to the first joist segment **70**, such as with fasteners **77**, to interconnect said first **70** and second **72** joist segments and form the first floor joist **62**.

The first floor joist **62** further has first **76** and second **78** joist sides. The first joist side **76** faces the front floor panel **22_F**, and the second joist side **78** faces the rear floor panel **22_R**. A first plurality of the brackets **64** is attached or secured to the first joist side **76**, with each one of these brackets **64** opposite a respective bracket **60** attached to the front floor panel **22_F**. A second plurality of the brackets **64** is attached or secured to the second joist side **78**, with each one of these brackets **64** opposite a respective bracket **60** attached to the rear floor panel **22_R**. As mentioned above, each pair of brackets **60, 64** receives one of the second floor joists **66**. The second floor joists **66** extend transverse to the front floor panel **22_F**, the rear floor panel **22_R**, and the first floor joist **62**, and extend substantially parallel to the first **22_{S1}** and second **22_{S2}** side floor panels and to one another. It should be appreciated that the floor frame **12** could include any number of first floor joists **62** and second floor joists **66**. Additionally, the arrangement of the first **62** and second **66** floor joists as shown in FIGS. 7 and 8 is not limited, and other arrangements of the first **62** and second **66** floor joists are also contemplated. The plurality of floor panels **22**, the first floor joist **62**, and the second floor joists **66** collectively form the floor frame **12**.

As shown at least in FIG. 8, the building assembly **10** further includes a floor board **80** supported by the floor frame **12**. The floor board **80** may be formed from any suitable flooring material, non-limiting examples of which include wood, plywood, fiberboard, synthetic materials such as laminate, etc. As shown in FIG. 8, the building assembly **10** includes a plurality of floor boards **80** disposed on the first **62** and second **64** joists and framed by the interconnected plurality of floor panels **22**. In an embodiment, each of the plurality of floor panels **22** has a ledge **82** extending inwardly from the inner side **28** of the floor panel **22** and positioned below the top surface **32**. The floor board(s) **80** is disposed on and supported by the ledges **82** of the interconnected floor panels **22**, the first floor joist **62**, and the second floor joists **66** to form a floor **83** of the building assembly **10**. The floor **83** is best shown in FIGS. 9, 14, 16, 17, 21-23, 25, and 29. In an embodiment, and as shown in FIG. 8, the floor board(s) **80** rests against the ledges **82** of the floor panels **22**, the first floor joist **62**, and the second floor joists **66**. In another embodiment, the floor board(s) **82** is secured to the ledges **82** of the floor panels **22**, the first floor joist **62**, and/or the second floor joists **66** with one or more fasteners.

The building assembly **10** includes the plurality of walls **16** as mentioned above. At least one of the plurality of walls **16** defines an opening **218** to provide access to the inside of the building assembly **10**. In the illustrated embodiment, and

with reference at least to FIG. 9, the plurality of walls **16** includes a front wall **16_F**, a rear wall **16_R** opposite the front wall **16_F**, a first side wall **16_{S1}**, and a second side wall **16_{S2}** opposite the first side wall **16_{S1}**. Each of the plurality of walls **16** includes a plurality of panels **84**, with each panel **84** defining a longitudinal axis **B** and having a length **L_P** extending along the longitudinal axis **B**. Each panel **84** has first **86** and second **88** ends, opposing inner **90** and outer **92** sides, and opposing top **94** and bottom **96** surfaces. The inner side **90** of each of the panels **84** faces inwardly toward the inside of the building assembly **10** and forms part of the building interior **18**. The outer side **92** of each of the panels **84** faces outwardly toward the environment **E** surrounding the building assembly **10** and forms part of the building exterior **20**. Additionally, and as best shown in FIG. 10, the inner **90** and outer **92** sides are spaced from one another, and each of the plurality of panels **84** has a slot **109** and first **110** and second **112** support ribs disposed in the slot **109**. The first **110** and second **112** support ribs extend between the first **86** and second **88** ends. Such a configuration of each of the panels **84** may be referred to as a slatwall configuration.

With reference to FIGS. 9-12, each panel **84** includes a mounting channel **98** formed in at least one of the inner **90** and outer **92** sides extending along the longitudinal axis **B** for removably securing an accessory **M** to at least one of the interior **18** and the exterior **20** of the building assembly **10**. In an embodiment, the mounting channel **98** is further defined as a first mounting channel **98** formed in the inner side **90** extending along the longitudinal axis **B** for removably securing the accessory **M** to the interior **18** of the building assembly **10**. Each panel **84** further includes a second mounting channel **100** formed in the outer side **92** extending along the longitudinal axis **B** for removably securing another accessory **M** to the exterior **20** of the building assembly **10**. The accessory **M** may be any object removably secured or attached to the interior **18** and/or exterior **20** of the building assembly **10**, non-limiting examples of which include shelves, hooks, storage baskets, storage cabinets, storage cubes, household items, plants, etc.

Details of the mounting channels **98**, **100** are described below at least with reference to FIGS. 10 and 11. Each of the first **98** and second **100** mounting channels are spaced from the top surface **94** of the panel **84**. In the illustrated embodiment, the first **98** and second **100** mounting channels are spaced a same distance **D_{MC1}**, **D_{MC2}** from the top surface **94** of the panel **84** such that the first mounting channel **98** is opposite the second mounting channel **100**. In an alternative configuration, the first **98** and second **100** mounting channels could be spaced a different distance from the top surface **94** such that the first mounting channel **98** is offset from the second mounting channel **100**. In an embodiment, each one of the plurality of panels **84** has the first **98** and second **100** mounting channels that are spaced a same distance **D_{MC1}**, **D_{MC2}** from the top surface **94**. In an alternative embodiment, some of the panels **84** could have the first **98** and second **100** mounting channels spaced the same distance from the top surface **94**, while other panels **84** could have the first **98** and second **100** mounting channels spaced a different distance from the top surface **94**. Additionally, one or more of the panels **84** could have only the first mounting channel **98** or only the second mounting channel **100**.

As best shown in FIG. 11, the first mounting channel **98** has a first channel depth **d₁** and the second mounting channel **100** has a second channel depth **d₂**. The first channel depth **d₁** of the first mounting channel **98** is the same as the second

channel depth **d₂** of the second mounting channel **100**. In an alternative configuration, the first **d₁** and second **d₂** channel depths could be different.

Each of the first **98** and second **100** mounting channels has a stem portion **102** and a chamber portion **104**. The chamber portion **104** has a larger cross-sectional area **A_C** compared to the cross-sectional area **A_S** of the stem portion **102**. Additionally, the stem portion **102** has a cross-sectional width **W_S** and the chamber portion **104** has a cross-sectional width **W_C** that is larger than the cross-sectional width **W_S** of the stem portion **102**. In the illustrated embodiment, each of the first **98** and second **100** mounting channels has a P-shaped configuration in cross-section. With this configuration of the first **98** and second **100** mounting channels, the accessory **M** can be easily attached to and removed from the interior **18** and exterior **20** of the building assembly **10**. For instance, and as shown in FIG. 12, the accessory **M** may be removably attached to the building assembly **10** utilizing a bracket **B**. In an embodiment, the bracket **B** is an 'S' bracket, where one end of the 'S' is secured to the accessory **M** and the other end of the 'S' bracket is disposed within the chamber portion **104** of the mounting channel **98**, **100** and held by the panel **84** defining the stem **102** and chamber **104** portions of the mounting channel **98**, **100**. It should be appreciated that other configurations of the mounting channel **98**, **100** are also contemplated as long as the accessory **M** can be suitably and/or readily attached to and removed from the interior **18** and exterior **20** of the building assembly **10**.

Referring at least to FIGS. 9 and 13, each panel **84** further includes an upper notch **106** formed through the top surface **94** and an opposing lower notch **108** formed through the bottom surface **96**. Each of the upper **106** and lower **108** notches is spaced inwardly along the longitudinal axis **B** from at least one of the first **86** and second **88** ends of the panel **84**. In an embodiment, the longitudinal axis **B** is further defined as a center axis **C** extending between the first **86** and second **88** ends of the panel **84**. With reference to FIG. 13, the upper notch **106** is formed through the top surface **94** of the panel **94** and extends toward but terminates prior to the center axis **C**. The lower notch **108** is formed through the bottom surface **96** and extends toward but terminates prior to the center axis **C**. In another embodiment, the upper notch **106** has an upper notch depth **D_{UN}** and the lower notch **108** has a lower notch depth **D_{LN}** with the upper notch depth **D_{UN}** the same as the lower notch depth **D_{LN}**. Additionally, the upper notch **106** has an upper notch width **W_{UN}** and the lower notch **108** has a lower notch width **W_{LN}** with the upper notch width **W_{UN}** the same as the lower notch width **W_{LN}**.

Each of the upper **106** and lower **108** notches has a cross-sectional configuration. As best shown in FIG. 13, the upper notch **106** has a first cross-sectional configuration and the lower notch **108** has a second cross-sectional configuration different from the first cross-sectional configuration. In an embodiment, the top surface **94** of each of the plurality of panels **84** defines a tongue **118** extending outwardly in a direction transverse to the longitudinal axis **B** and the bottom surface **96** of each of the plurality of panels **84** defines a groove **120** extending inwardly in a direction transverse to the longitudinal axis **B**. The cross-sectional configuration of the upper notch **106** is defined by the cross-sectional configuration of the inner **90** and outer **92** sides of the panel **84** and the tongue **118**. This is different from the cross-sectional configuration of the lower notch **108**, which is defined by the cross-sectional configuration of the inner **90** and outer **92** sides of the panel **84** and the groove **120**.

11

As previously mentioned, and as shown in FIGS. 10, 12, and 13, each of the plurality of panels 84 has the slot 109 and the first 110 and second 112 support ribs disposed in the slot 109 and extending between the first 86 and second 88 ends. As best shown in FIG. 13, the upper notch 106 extends between the top surface 94 and the first support rib 110, and the lower notch 108 extends between the bottom surface 96 and the second support rib 112. The first support rib 110 is substantially parallel to the top surface 94 of the panel 84 and defines a base 114 of the upper notch 106, and the second support rib 112 is substantially parallel to the bottom surface 96 of the panel 84 and defines a base 116 of the lower notch 108. Each of the support ribs 110, 112 extends along the entire length of the panel 84. In an alternative configuration, one or more of the support ribs 110, 112 could extend along a portion of the length of the panel 84. It should be appreciated that the panels 84 could have additional support ribs, and one or more of the support ribs could extend at least partially along the longitudinal axis B of each panel 84.

As mentioned above, the top surface 94 of each of the panels 84 defines the tongue 118 and the bottom surface of each of the panels 84 defines the groove 120. As best shown in FIG. 10, the top surface 94 has a stepped profile with the top step forming the tongue 118. The tongue 118 has a substantially flat upper surface 122, a base 128 opposite the upper surface 122, and first 124 and second 126 side surfaces both extending from the upper surface 122 at an angle offset from 90°. With this configuration, the base 128 of the tongue is wider in cross-section than the upper surface 122. As also mentioned above, the bottom surface 96 defines the groove 120. The cross-sectional configuration of the groove 120 is complementary to that of the tongue 118 so that the groove 120 of one panel 84 can readily receive the tongue 118 of an adjacent panel 84 to form the walls 16. As shown in FIGS. 9, 12, and 13, the tongue 118 of one of the plurality of panels 84 mates with the groove 120 of an adjacent one of the plurality of panels 84 to form one of the plurality of walls 16. This is accomplished by placing one panel 84 over an adjacent panel 84 such that the tongue 118 of the adjacent panel 84 is received within the groove 120 of the one panel 84 to stack the plurality of panels 84 and form one of the walls 16. This is illustrated at least in FIGS. 9 and 13.

The stepped profile of the top surface 94 of each of the plurality of panels 84 defines a ledge 129, as shown in FIGS. 10 and 13. As best shown in FIG. 13, when adjacent panels 84 are joined to one another (by mating the tongue 118 of one of the panels 84 with the groove 120 of an adjacent one of the panels 84), a portion of the bottom surface 96 of the panel 84 remains exposed. The exposed portion of the bottom surface 96 of the one of the panels 84 and the ledge 129 of an adjacent one of the panels 84 form a channel 128 between the adjacent panels 84. The channel 128 extends along the longitudinal axis B. In the illustrated embodiment, the channel 128 has the same configuration as the stem portion 102 of the first 98 and second 100 mounting channels such that the channel 128 and the second mounting channel 100 look similar when viewed from either the inside or the outside of the building assembly 10.

With reference to FIGS. 9 and 13-15, and in an embodiment, each of the plurality of walls 16 includes a base panel 130 defining a longitudinal axis D, and has first 132 and second 134 ends and opposing top 136 and bottom 138 surfaces. The base panel 130_F of the front wall 16_F and the base panel 130_R of the rear wall 16_R has a first base panel configuration, and the base panel 130_{S1} of the first side wall 16_{S1} and the base panel 130_{S2} of the second side wall 16_{S2}

12

has a second base panel configuration different from the first base panel configuration. For example, the base panel 130_F, 130_R of the front 16_F and rear 16_R walls has a first panel width W_{P1} and the base panel 130_{S1}, 130_{S2} of each of the first 16_{S1} and second 16_{S2} side panels has a second panel width W_{P2} twice the first panel width W_{P1}. In this example, the base panel 130_F, 130_R of each of the front 16_F and rear 16_R walls may be referred to herein as a half or partial base panel. The base panel 130_{S1}, 130_{S2} of each of the first 16_{S1} and second 16_{S2} side walls may be referred to herein as a full or whole base panel. In an embodiment, the whole base panel 130_{S1}, 130_{S2} has the same configuration as each of the plurality of panels 84.

Each of the base panels 130 has an upper notch 140 formed through the top surface 136 spaced inwardly along the longitudinal axis D from each of the first 132 and second 134 ends. Each of the whole base panels 130 also has a lower notch 142 formed through the bottom surface 138 spaced inwardly along the longitudinal axis D from each of the first 132 and second 134 ends. Notably, none of the half base panels 130 has a lower notch. Additionally, the top surface 136 of each of the base panels 130 defines a tongue 150 extending outwardly in a direction transverse to the longitudinal axis D, and the bottom surface 138 of each of the base panels 130 defines a groove 152 extending inwardly in a direction transverse to the longitudinal axis D.

The base panels 130 are coupled to the floor frame 12 as follows. One of the half base panels 130_R is disposed over and coupled to the rear floor panel 22_R by receiving the tongue 46 of the rear floor panel 22_R in the groove 152 of the half base panel 130_R to initiate formation of the rear wall 16_R, as shown in FIG. 15. Another one of the half base panels 130_F is disposed over and coupled to the front floor panel 22_F by receiving the tongue 46 of the front floor panel 22_F in the groove 152 of the half base panel 130_F to initiate formation of the front wall 16_F. Then, one of the whole base panels 130_{S2} is disposed over and coupled to the second side wall 16_{S2} by receiving the tongue 46 of the second side floor panel 22_{S2} in the groove 152 of the whole base panel 130_{S2} to initiate formation of the second side wall 16_{S2}, as shown in FIG. 15. The other one of the whole base panels 130_{S1} is disposed over and coupled to the first side floor panel 22_{S1} by receiving the tongue 46 of the first side floor panel 22_{S1} in the groove 152 of the whole base panel 130_{S1} to initiate formation of the first side wall 16_{S1}. Additionally, the lower notches 142 formed in the bottom surface 138 of the whole base panel 130_{S1}, 130_{S2} mates with respective upper notches 140 formed in the top surface 136 of the half base panel 130_F, 130_R to interconnect the base panels 130_F, 130_R, 130_{S1}, 130_{S2}.

The plurality of walls 16 are interconnected to one another as the individual walls 16 are formed by stacking the panels 84. Interconnection of the plurality of walls 16 is described below at least with reference to FIG. 9. In an embodiment, the plurality of panels 84 includes first 144 and second 146 panels. The lower notch 108 of the first panel 144 mates with the upper notch 106 of the second panel 146 to form an interlocking joint 148 between the first 144 and second 146 panels to interconnect the first 144 and second 146 panels and form adjacent interconnected walls 16 of the plurality of walls 16 of the building assembly 10. Such a connection between the first 144 and second 146 panels may be referred to as a saddle notch connection, which is accomplished without requiring any tools. In an embodiment, the first panel 144 is one of a plurality of first panels 144 each having the first 86 and second 88 ends, and the second panel 146 is one of a plurality of second panels 146

each having the first **86** and second ends **88**. The interlocking joint **148** is further defined as a plurality of interlocking joints **148** each formed between one of the plurality of first panels about the first end **86** of the first panel **144** and one of the plurality of second panels about the second end **88** of the second panel **146** to interconnect the plurality of first panels **144** and the plurality of second panels **146** to partially form adjacent walls **16** of the plurality of walls **16** of the building assembly **10**.

In an embodiment, the adjacent walls **16** are further defined as the front **16_F** and first side **16_{S1}** walls, and the plurality of panels **84** further includes a third panel **154**. The lower notch **108** of third panel **154** mates with the upper notch **106** of the second panel **146** to form a second interlocking joint **156** between the second **146** and third **154** panels. Additionally, the third panel **154** is one of a plurality of third panels **154** each having the first **86** and second **88** ends and the second interlocking joint **156** is further defined as a plurality of second interlocking joints **156**. Each of the second interlocking joints **156** is formed between one of the plurality of second panels **146** about the first end **86** of the second panel **146** and one of the plurality of third panels **154** about the second end **88** of the third panel **154** to interconnect the plurality of second panels **146** and the plurality of third panels **154** to partially form the rear wall **16_R** adjacent the first side wall **16_{S1}** of the plurality of walls **16** of the building assembly **10**.

The plurality of panels **84** further includes a fourth panel **158** and the lower notch **108** of the third panel **154** mates with the upper notch **106** of the fourth panel **158** to form a third interlocking joint **160** between the third **154** and fourth **158** panels. The fourth panel **158** is one of a plurality of fourth panels **158** each having the first **86** and second **88** ends, and the third interlocking joint **160** is further defined as a plurality of third interlocking joints **160**. Each of the third interlocking joints **160** is formed between one of the plurality of third panels **154** about the first end **86** of the third panel **154** and one of the plurality of fourth panels **158** about the second end **88** of the fourth panel **158** to interconnect the plurality of third panels **154** and the plurality of fourth panels **158** to partially form the second side wall **16_{S2}** adjacent the rear wall **16_R** of the plurality of walls **16** of the building assembly **10**.

The upper notch **106** of the fourth panel **158** mates with the lower notch **108** of the first panel **144** to form a fourth interlocking joint **162** between the first **144** and fourth **158** panels. The fourth interlocking joint **162** is further defined as a plurality of fourth interlocking joints **162** each formed between one of the plurality of fourth panels **158** about the first end **86** of the fourth panel **158** and one of the plurality of first panels **144** about the second end **88** of the first panel **144** to interconnect the plurality of fourth panels **158** and the plurality of first panels **144**.

In an embodiment, and as shown at least in FIG. 13, the building assembly **10** further includes a plurality of caps **260** coupled to at least one of the first **86** and second **88** ends of each of the plurality of panels **84**. Each cap **260** is configured to enclose the slot **109** of a respective one of the panels **84** at one or more of the first **86** and second **88** ends. Each of the plurality of caps **260** has a head **262** disposed over the at least one of the first **86** and second **88** ends of a respective one of the plurality of panels **84**. Each of the plurality of caps **260** further has a stem **264** extending from the head **262**. The stem **264** is disposed within the mounting channel **98**, **100** to mount the cap **260** to the at least one of the first **86** and second **88** ends of the respective one of the plurality of panels **84**. In the illustrated embodiment, the cap **260** has

two stems **264**, with one of the stems **264** disposed within the first mounting channel **98** and the other one of the stems **264** disposed within the second mounting channel **100**. Other configurations of the cap **260** are also contemplated.

In an embodiment, and with reference at least to FIG. 16, the plurality of panels **84** of each of the plurality of walls **16** has a first section of panels **164** and a second section of panels **166** spaced from the first section of panels **164**. Each panel **84** of the first section of panels **164** has the first end **86**, a first segment end **168** opposite the first end **86**, the upper notch **106** formed through the top surface **94**, and the opposing lower notch **108** formed through the bottom surface **96**. The upper **106** and lower **108** notches are spaced inwardly along the longitudinal axis **B** from the first end **86**. Each panel **84** of the second section of panels **166** has the second end **88**, a second segment end **170** opposite the second end **88**, the upper notch **106** formed through the top surface **94**, and the opposing lower notch **108** formed through the bottom surface **96**. The upper **106** and lower **108** notches are spaced inwardly along the longitudinal axis **B** from the second end **88**.

The building assembly **10** further includes a panel frame **172** disposed between the first **164** and second **166** sections of panels. With reference to FIGS. 16 and 17, the panel frame **172** is connected to the first segment end **168** of each panel **84** of the first section of panels **164** and connected to the second segment end **170** of each panel **84** of the second section of panels **166** to interconnect the first **164** and second **166** sections of panels of the wall **16**. In an embodiment, the panel frame **172** is further defined as a first side panel frame **172_{S1}** connected to the first **164** and second **166** sections of panels of the first side wall **16_{S1}**. The building assembly **10** further includes a rear panel frame **172_R** connected to the first segment end **168** of each panel **84** of the first section of panels **164** and connected to the second segment end **170** of each panel **84** of the second section of panels **166** to interconnect the first **168** and second **170** sections of panels of the rear wall **16_R**. The building assembly **10** further includes a second side panel frame **172_{S2}** connected to the first segment end **168** of each panel **84** of the first section of panels **164** and connected to the second segment end **170** of each panel **84** of the second section of panels **166** to interconnect the first **168** and second **170** sections of panels of the second side wall **16_{S2}**. Additionally, the building assembly **10** further includes a front panel frame **172_F** connected to the first segment end **168** of each panel **84** of the first section of panels **164** and connected to the second segment end **170** of each panel **84** of the second section of panels **166** to interconnect the first **168** and second **170** sections of panels of the front wall **16_F**.

The configuration of the panel frame **172_{S1}** and **172_{S2}** of the first **16_{S1}** and second **16_{S2}** walls, respectively, is described with reference to FIGS. 16-18. Each of the panel frames **172_{S1}**, **172_{S2}** defines a longitudinal axis **E**, and has a length **L_{SPF}** extending along the longitudinal axis **E**. Each of the panel frames **172_{S1}**, **172_{S2}** further has first **174** and second **176** ends and opposing first **178** and second **180** sides. The first side **178** defines a first channel **182** extending along the longitudinal axis **E**, and the second side **180** defines a second channel **184** also extending along the longitudinal axis **E**. The first channel **182** receives the first segment end **168** of each of the panels **84** of the first section of panels **164** of the first side wall **16_{S1}** and the second channel **184** receives the second segment end **170** of each of the panels **84** of the second section of panels **166** of the first side wall **16_{S1}** to interconnect the first **164** and second **166** sections of panels of the first side wall **16_{S1}**. Similarly, the

first channel 182 receives the first segment end 168 of each of the panels 84 of the first section of panels 164 of the second side wall 16_{S2} and the second channel 184 receives the second segment end 170 of each of the panels 84 of the second section of panels 166 of the second side wall 16_{S2} to interconnect the first 164 and second 166 sections of panels of the second side wall 16_{S2}.

The configuration of the panel frame 172_R of the rear wall 16_R is described with reference to FIGS. 16, 17, and 19. The panel frame 172_R of the rear wall 16_R defines a longitudinal axis F, and has a length L_{RPF} extending along the longitudinal axis F. The panel frame 172_R further has first 186 and second 188 ends and opposing first 190 and second 192 sides. The first side 190 defines a first channel 194 extending along the longitudinal axis F, and the second side 192 defines a second channel 196 also extending along the longitudinal axis F. The first channel 194 receives the first segment end 168 of each of the panels 84 of the first section of panels 164 of the rear wall 16_R, and the second channel 184 receives the second segment end 170 of each of the panels 84 of the second section of panels 166 of the rear wall 16_R.

In an embodiment, each of the panel frames 172_{S1}, 172_{S2}, 172_R has first 198 and second 200 frame segments each defining a slot 202. Additionally, one of first 198 and second 200 frame segments of the panel frame 172_{S1}, 172_{S2}, 172_R has a tab 204. The tab 204 of the one of the first 198 and second 200 frame segments is disposed within the slot 202 of the other one of the first 198 and second 200 frame segments to interconnect said first 198 and second 200 frame segments to form the panel frame 172_{S1}, 172_{S2}, 172_R. In an embodiment, the one of the first 198 and second 200 frame segments has two tabs 204. It should be appreciated that the one of the first 198 and second 200 frame segments may any number of tabs 204.

The first frame segment 198 has the first end 186 of the panel frame 172 and a first segment end 206, and the second frame segment 200 has the second end 186 of the panel frame 172 and a second segment end 208. In the embodiment shown, the tab 204 extends from the second segment end 208 of the second frame segment 200 along the longitudinal axis F. The tab 204 may be secured to the second frame segment 200 about the second segment end 208 in any suitable fashion, such as with one or more fasteners. The tab 204 extends from the second segment end 208 of the second frame segment 200 and into the slot 202 of the first frame segment 198. The tab 204 may be secured to the first frame segment 198 in any suitable fashion, such as with one or more fasteners.

The configuration of the panel frame 172_F of the front wall 16_F is described with reference to FIGS. 16 and 17. The panel frame 172_F has an upper side 210, a lower side 212 opposite the upper side 210, a first side 214, and a second side 216 opposite the first side 214. The upper 210, lower 212, first 214, and second 216 sides are interconnected to define the opening 218 for providing access to the inside of the building assembly 10. This panel frame 172_F may be further defined herein as a door frame. The upper side 210 of the panel frame 172_F defines a first channel 220, the lower (or bottom) side 212 of the panel frame 172_F defines a second channel 222, the first side 214 of the panel frame 172_F defines a third channel 224, and the second side 216 of the panel frame 172_F defines a fourth channel 226. In an embodiment, the building assembly includes a bracket 209 coupled to the upper side 210 of the panel frame 172_F, and the building assembly 10 includes a window frame 298 configured to mate with the bracket to secure the window frame 298 to the panel frame 172_F. In another embodiment,

the first channel 220 of the upper side 210 could receive a tongue of the window frame 298 to at least partially support the window frame 298. Further details of the window frame 298 are described below. Additionally, the second channel 222 of the lower side 212 receives the tongue 46 of the front floor panel 22_F such that the panel frame 172_F is supported by the floor frame 12. The third channel 224 of the first side 214 receives the first segment end 168 of each of the panels 84 of the first section of panels 164 of the front wall 16_F and the fourth channel 226 of the second side 216 receives the second segment end 170 of each of the panels 84 of the second section of panels 166 of the front wall 16_F to interconnect the first 164 and second 166 sections of panels of the front wall 16_F. The panels 84 could rest within the channels 224, 226, or could be secured to the panel frame 172_F with one or more fasteners.

In an embodiment, and as best shown in FIG. 1, the building assembly 10 includes a door 230 coupled to at least one of the plurality of walls 16. As previously mentioned, the panel frame (or door frame) 172_F defines the opening 218. The door 230 is coupled to the panel frame 172_F and movable between an open position in which the door 230 is spaced from the opening 218 and a closed position in which the door 230 covers the opening 218. The door 230 in the closed position is shown in FIG. 1. In an embodiment, the building assembly 10 could include a plurality of doors 230 coupled to the same or different walls 16. For example, the building assembly 10 could have two doors 230 (as illustrated in FIG. 1) coupled to the panel frame 172_F and both movable (such as in opposite directions) between the open and closed positions. The door 230 may be formed from any suitable material, including hard materials, soft materials, transparent materials, opaque materials, etc. Additionally, the door 230 may have any suitable configuration. In another embodiment, the building assembly 10 does not include door and the opening 218 remains open for access to the inside of the building assembly 10.

As the first 144 and second 146 panels of the plurality of walls 16 are interconnected at a position inward from the ends 86, 88, the interconnected panels 144, 146 form a space 232 defined between respective portions of the first 144 and second 146 panels extending outwardly from the interlocking joint 148. This is shown, for example, in FIG. 16. Referring to FIGS. 16, 17, and 20, the building assembly 10 includes a post 234 extending between the floor frame 12 and the roof 14 enclosing the space 232 defined by the respective portions of the first 144 and second 146 panels extending outwardly from the interlocking joint 148. The post 232 defines a corner 236 of the exterior 20 of the building assembly 10.

In the illustrated embodiment, the building assembly has a quadrilateral configuration and includes four posts 234, with one of the posts 234 defining one of four corners of the building assembly 10. Accordingly, one of the posts 234 encloses a space 232 defined by the respective portions of the first 144 and second 146 panels extending outwardly from the interlocking joint 148 to define the corner 236. This corner 236 is referred to herein as a first corner 236. Another one of the posts 234 encloses a space 232 defined by respective portions of the second 146 and third 154 panels extending outwardly from the second interlocking joint 156 to define a second corner 238. Another one of the posts 234 encloses a space 232 defined by respective portions of the third 154 and fourth 158 panels extending outwardly from the third interlocking joint 160 to define a third corner 240. Additionally, another one of the posts 234 encloses a space 232 defined by respective portions of the fourth 158 and first

144 panels extending outwardly from the fourth interlocking joint 162 to define a fourth corner 242.

In an embodiment, the post 234 has first 244 and second 246 post segments. Each of the first 244 and second 246 post segments defines a longitudinal axis G, and has a length L_{POST} extending along the longitudinal axis G. The lengths L_{POST} of the segments 244, 246 may be the same or different. Additionally, each of the first 244 and second 246 post segments defines a slot 248, and one of the first 244 and second 246 post segments has a tab 250. The tab 250 of the one of the first 244 and second 246 post segments is disposed within the slot 248 of the other one of the first 244 and second 246 post segments to interconnect said first 244 and second 246 post segments to form the post 234. In an embodiment, the one of the first 244 and second 246 post segments has a single tab 250. Alternatively, the one of the first 244 and second 246 post segments could have any number of tabs 250. The tab 250 may be secured to each of the first 244 and second 246 post segments in any suitable fashion, such as with one or more fasteners.

In certain embodiments, the posts 234 may operate to cover the space 232 defined between adjacent panels 84 to form the corners 236, 238, 240, 242 of the building assembly 10. In this respect, the posts 234 contribute to the ornamentality of the building assembly 10. In other embodiments, the panels 84 of adjacent walls 16 could be secured to the respective post 234, such as with one or more fasteners, and/or the roof 14 may be coupled to the posts 234 such that the posts 234 also operate as a structural feature of the building assembly 10. In these embodiments, and the posts 234 become part of a skeleton 400 of the building assembly 10. Further details of the skeleton 40 are described below.

Details of the roof 14 and how the roof 14 is interconnected to the walls 16 and the floor frame 12 of the building assembly 10 are described below with reference to FIGS. 21-30. The roof 14 has a plurality of roof beams 266 coupled to the plurality of panels 84 of each of the plurality of walls 16. Each roof beam 266 has a roof panel 268 and a roof bracket 270 coupled to the roof panel 268. The roof bracket 270 has a C-shaped configuration defining a channel 272. The roof panel 268 has opposing top 274 and bottom 276 surfaces. The roof bracket 270 is disposed on the roof panel 268 with the top surface 274 of the roof panel 268 received within the channel 272 of the roof bracket 270. The bottom surface 276 of the roof panel 268 defines a groove 278. The tongue 118 of the upper-most panel 84 of the wall 16 is received within the groove 278 of the roof panel 268 to couple the roof panel 268 to the upper-most panel 84 of the wall 16.

In an embodiment, building assembly 10 has a first side roof beam 266_{S1}, a second side roof beam 266_{S2}, and a rear roof beam 266_R. The first side roof beam 266_{S1} is coupled to the upper-most panel 84 of the first section of panels 164 of the first side wall 16_{S1}. The second side roof beam 266_{S2} is coupled to the upper-most panel 84 of the second section of panels 166 of the second side wall 16_{S2}. The roof panel 268 of each of the first 266_{S1} and second 266_{S2} side roof beams defines a longitudinal axis H, and has first 280 and second 282 ends and an upper notch 284 spaced inwardly along the longitudinal axis H from the first end 280. The roof bracket 270 is shorter in length than the roof panel 268 of each of the first 266_{S1} and second 266_{S2} side roof beams and is positioned adjacent the second end 282 such that the roof bracket 270 does not cover the upper notch 284.

The rear roof beam 266_R is coupled to the upper-most panel 84 of both the first 164 and second 166 sections of panels of the rear wall 16_R. For example, and as best shown

in FIG. 21, the rear roof beam 266_R has first 286 and second 288 roof beam segments, with the first roof beam segment 286 coupled to the first section of panels 164 of the rear wall 16_R and the second roof beam segment 288 coupled to the second section of panels 166 of the rear wall 16_R. The first roof beam segment 286 has a lower notch 290 spaced inwardly from the second end 282 of the roof panel 268, and the second roof beam segment has a lower notch 290 spaced inwardly from the first end 280 of the roof panel 268.

10 The first roof beam segment 286 has the second end 282 and a first segment end 292, and the second roof beam segment 288 has the first end 280 and a second segment end 294. The first segment end 292 is received within the first channel 194 of the rear panel frame 172_R, and the second segment end 294 is received within the second channel 196 of the rear panel frame 172_R. Fasteners may be used to interconnect the rear roof beam 266_R with the panel frame 172_R.

15 During assembly, and with reference to FIGS. 21 and 22, the roof beam 266_{S1} of the first side wall 16_{S1} is coupled to the upper-most panel 84 of the first side wall 16_{S1}, and the roof beam 266_{S2} of the second side wall 16_{S2} is coupled to the upper-most panel 84 of the second side wall 16_{S2}. The rear roof beam 266_R is coupled to the upper-most panel 84 of the rear wall 16_R. In doing so, the lower notch 290 about the first end 280 of the roof panel 268 of the rear roof beam 266_R mates with the upper notch 284 of the roof panel 268 of the roof beam 266_{S1} of the first side wall 16_{S1}. The lower notch 290 about the second end 282 of the roof panel 268 of the rear roof beam 266_R mates with the upper notch 284 of the roof panel 268 of the roof beam 266_{S2} of the second side wall 16_{S2}. The coupling of the upper 284 and lower 290 notches interconnects the roof beams 266_{S1}, 266_R, 266_{S2} to partially form a roof frame 296.

20 In an alternative embodiment, adjacent roof beams 266_{S1}, 266_R could be secured to a respective post 234, and adjacent roof beams 266_R, 266_{S2} could be secured to a respective post 234. The roof beams 266_{S1}, 266_R, 266_{S2} may be secured to the posts 234 by any suitable means, such as with one or 25 more fasteners. Additionally, the roof beam 266_{S1} may be secured to the panel frame 172_{S1} of the first side wall 16_{S1}, and the roof beam 266_{S2} may be secured to the panel frame 172_{S2} of the second side wall 16_{S2}. The roof beams 266_{S1}, 266_{S2} may be secured to the respective panel frames 172_{S1}, 172_{S2} by any suitable means, such as with one or more fasteners. As mentioned above, the roof beam segments 292, 294 of the roof beam 266_R are secured to the panel frame 172_R. In this alternative embodiment, the roof beams 266_{S1}, 266_R, 266_{S2}, the posts 234, and the panel frames 172_{S1}, 172_R, 172_{S2} form part of the skeleton 400 of the building assembly 10.

30 With reference to FIGS. 22 and 23, the front wall 16_F is formed from the plurality of first panels 144 and further includes the front window frame 298 supported by the plurality of first panels 144. The front window frame 298 supports at least one window pane 300. In an embodiment, the front window frame 298 is a single piece supporting a single window pane 300, such as shown in FIG. 31. In another embodiment, the front window frame 298 has multiple pieces supporting a plurality of window panes 300, such as shown at least in FIGS. 22 and 23. For example, as shown in FIG. 22, the front window frame 298 has first 302, second 304, and third 306 frame members. The first frame member 302 is sandwiched between the second 304 and third 306 frame members, and the frame members 302, 304, 306 are interconnected. For example, the first frame member 302 includes brackets 308 extending from opposing sides,

and each of the second 304 and third 306 frame members defines a channel 310 for receiving the brackets 308. The brackets 308 may be secured to the frame members 304, 306 by any suitable means, such as with fasteners, to secure the side frame members 304, 306 to the first frame member 302.

As show in FIG. 22, the front window frame 298 has top 309 and bottom 311 segments, first 312 and second 314 side segments, and a front window bracket 316 extending from at least one of the first 312 and second 314 side segments. In the illustrated embodiment, a front window bracket 316 extends from each of the first 312 and second 314 side segments. The front window bracket 316 has upper 318 and lower 320 surfaces and a slot 322 defined through the upper surface 318.

During assembly, the first frame member 302 of the front window frame 298 is coupled to the panel frame (door frame) 172_F of the front wall 16_F, as shown in FIG. 22. In an embodiment, the bottom segment 311 of the front window frame 298 defines a channel configured to receive the bracket 209 coupled to the upper side 210 of the panel frame 172_F, to secure the window frame 298 to the panel frame 172_F. Alternatively, the bottom segment 311 of the front window frame 298 could include a tongue configured to mate with the first channel 220 of the upper side 210 of the panel frame 172_F. Then, the second 304 and third 306 frame members are coupled to opposite sides of the first frame member 302 (via the bracket/channel mechanism described above). The front window brackets 316 extending from the first 312 and second 314 side segments are disposed within the slot 248 of the respective posts 234. Additionally, the panel frame 172_F and the plurality of panels 84 of the front wall 16_F supports the front window frame 298.

Turning to FIGS. 23 and 23A, the first side wall 16_{S1} adjacent the front wall 16_F is formed from the plurality of second panels 146 and includes a side window frame 324 supported by the plurality of second panels 146. The side window frame 324 supports a window pane 325. The side window frame 324 has first 326 and second 328 side segments, a first window bracket 330 extending from the first side segment 326, and a second window bracket 331 extending from the second side segment 328. The first window bracket 330 is received within the channel 184 of the panel frame 172_{S1}. In an embodiment, the first window bracket 330 is secured to the panel frame 172_{S1} by any suitable means, such as with one or more fasteners 354. The second window bracket 331 has upper 332 and lower 334 surfaces and a slot 336 defined through the lower surface 334.

The first side wall 16_{S2} adjacent the front wall 16_F is formed from the plurality of fourth panels 158 and includes a side window frame 338 supported by the plurality of fourth panels 158. The side window frame supports a window pane 340. The side window frame 338 has first 342 and second 344 side segments, a first window bracket 346 extending from the first side segment 342, and a second window bracket 347 extending from the second side segment. The first window bracket 346 is received within the channel 182 of the panel frame 172_{S2}. In an embodiment, the first window bracket 346 is secured to the panel frame 172_{S2} by any suitable means, such as with one or more fasteners 354. The second window bracket 347 has upper 348 and lower 350 surfaces and a slot 352 defined through the lower surface 350.

During assembly, the side window frame 324 is coupled to the upper-most panel 84 of the plurality of second panels 146 of the first side wall 16_{S1}. At the same time, the slot 336 of the bracket 331 extending from the second side segment

326 mates with the slot 322 of the first window frame segment 312 of the front window frame 298 to interconnect the front 298 and side 324 window frames. Similarly, the side window frame 338 is coupled to the upper-most panel 84 of the plurality of fourth panels 158 of the second side wall 16_{S2}. At the same time, the slot 352 of the bracket 347 extending from the second side segment 344 of the side window frame 338 mates with the slot 322 of the second window frame segment 314 of the front window frame 298 to interconnect the front 298 and side 338 window frames.

In certain embodiments, and with reference to FIG. 24, the post 234 extending between the floor frame 12 and the roof 14 adjacent the front 16_F and first side 16_{S1} walls further has first 356 and second 358 post sides arranged adjacent one another. When the brackets 316, 331 are coupled, the front window bracket 316 is positioned adjacent the second post side 358 and the side window bracket 331 is positioned adjacent the first post side 356. Fasteners 360 may be used to secure the front window bracket 316 to the second post side 358 and fasteners may be used to secure the side window bracket 331 to the first post side 356 to interconnect the front window frame 298, the side window frame 324, and the post 234. It is to be appreciated that the front window frame 298 and the side window frame 338 may be secured to the post 234 extending between the front wall 16_F and the second side wall 16_{S2} in the same fashion to interconnect the front window frame 298, the side window frame 338, and the post 234. The front window frame 298, the side window frames 324, 338, and the posts 234, in this embodiment, form part of the skeleton 400 of the building assembly.

In another embodiment, and as shown in FIG. 25, the post 234 extending between the floor frame 12 and the roof 14 adjacent the front 16_F and first side 16_{S1} walls has a shelf 362. The shelf 322 is disposed within the slot 248 and secured to the post 234. For example, the shelf 362 may be integral with the post 234, or may be secured to the post 234 with one or more fasteners. The shelf 362 is located below the coupled brackets 316, 331 of the window frames 298, 324 and is configured to separate the front 298 and side 324 window frames from the plurality of panels 84. In an embodiment, the lower surface of the front window bracket 316 and the lower surface of the side window bracket 331 are spaced from the shelf 362. In an alternative embodiment, the lower surface of the front window bracket 316 and the lower surface of the side window bracket 331 could be seated against the shelf 362. In an embodiment, the post 234 adjacent the front 16_F and second side 16_{S2} walls also includes a shelf 362. A further description of the shelf 362 is set forth below in connection with FIG. 31.

As previously mentioned, the interconnected roof beams 266 at least partially form the roof frame 296. In an embodiment, the front window frame 298 and the side window frames 324, 338 in combination with the interconnected roof beams 266 at least partially form the roof frame 296. In another embodiment, and as shown in FIG. 26, the roof frame 296 further includes a roof joist 364. The roof joist 364 is coupled to and extends between the panel frames 172_{S1} and 172_{S2} of the first 16_{S1} and second 16_{S2} side walls, and extends substantially parallel to the front 16_F and rear 16_R walls. Alternatively, the roof joist 364 could extend between the front 16_F and rear 16_R walls and substantially parallel to the first 16_{S1} and second 16_{S2} side walls. The roof joist 364 is attached to the panel frames 172_{S1} and 172_{S2} by any suitable means, such as with brackets as described above for attaching the floor joist 62 to the floor panels 22_{S1} and 22_{S2}. The roof joist 364 may have the same configuration as the floor joist 62 described in detail above. The roof joist 364

21

becomes part of the roof frame 296 and serves to add additional support for at least one roof board 366 disposed on and secured to the roof frame 296.

Referring to FIGS. 27-30, the roof 14 of the building assembly 10 further includes the at least one roof board 366 secured to the roof frame 296. In an embodiment, the at least one roof board 366 is secured to at least one of the roof beams 266, the window frames 298, 324, 338, and the roof joist 364 utilizing fasteners or the like. The roof board(s) 366 may be formed from any suitable roofing material, such as hard materials, soft materials, transparent materials, opaque materials, etc. In an embodiment, the roof 14 could also include roof tiles or shingles.

In an embodiment, the at least one roof board 366 is further defined as a plurality of front roof boards 366_F and a plurality of rear roof boards 366_R adjacent the plurality of front roof boards 366_F. Each of the front roof boards 366_F has front 368 and back 370 sides. At least the front roof board 366_F has a flange 372 extending from the back side 370 and overlapping a respective one of the plurality of rear roof boards 366_R to form a first seal between the plurality of front roof boards 366_F and the plurality of rear roof boards 366_F.

In another embodiment, the plurality of front roof boards 366_F has a plurality of interconnected sheets of material including a top sheet 374, a bottom sheet 376 spaced from the top sheet 374, and at least one middle sheet 378 sandwiched between the top 374 and bottom 376 sheets. Each one of the rear roof boards 366_R has front 380 and back 382 sides and at least one flange 384 extending from the front side 380 of the rear roof panel 366_R and with the at least one middle sheet 378 of the plurality of front roof boards 366_F overlapping the flange 384 of the rear roof board 366_R to form a second seal between the plurality of front roof panels 366_F and the plurality of rear roof boards 366_R. It should be appreciated that the front 366_F and rear 366_R roof panels could be reversed, and the rear roof panel 366_R could have a flange overlapping the top sheet of the front roof panel 366_F and the front roof panel 366_F could have a flange with the middle sheet of the rear roof panel 366_R overlapping the flange of the front roof panel 366_F. Additionally, the panels 366_F, 366_R could be configured such that the flanges overlap the respective sheets, rather than as described above.

Once the front 366_F and rear 366_R roof boards have been interconnected, the roof boards 366_F, 366_R are disposed on and secured to the roof frame 296 with, for example, one or more fasteners. Alternatively, the roof boards 366_F, 366_R may be interconnected as each roof board 366_F, 366_R is disposed on and secured to the roof frame 296.

As previously mentioned, at least one of the plurality of walls 16 defines an opening 218 to provide access to the inside of the building assembly 10. The plurality of walls 16 may also define an additional opening(s) 390 for forming a window of the building assembly 10. As shown in FIG. 21, for example, additional openings 390 are defined by each of the first 16_{S1} and second 16_{S2} side walls. In an embodiment, the building assembly 10 includes a window frame 392 coupled to the plurality of panels 84 of the first side wall 16_{S1}, and the window frame 392 defines one of the openings 390. The building assembly 10 further includes another window frame 394 coupled to the plurality of panels 84 of the second side wall 16_{S2}, and the window frame 394 defines another one of the openings 390. The window frames 392, 394 may be coupled to the panels 84 in the same fashion as the panel frames 172 described in detail above.

22

In certain embodiments, the building assembly 10 relies at least on the stacked panels 84 of the plurality of walls 16 for structural support. In other embodiments, the building assembly 10 relies on the floor frame 12, the posts 234, at least one roof beam 266, at least one of the panel frames 172, and at least one of the window frames 298, 324, 338 for structural support. These components in combination form a skeleton 400 of the building assembly 10, such as shown in FIG. 31. For example, the skeleton 400 includes the floor frame 12 having the plurality of interconnected floor panels 22, at least one of the roof beams 266 spaced from the floor frame 12, and the plurality of posts 234 extending between and coupled to the floor frame 12 and the roof beams 266 to interconnect the floor frame 12 and the at least one roof beam 266. The skeleton 400 further includes at least one of the panel frames 172 extending between the floor frame and the at least one roof beam 266 to interconnect the floor frame 12 and the at least one roof beam 266, and at least one window frame 298, 324, 338. FIG. 31 shows the skeleton 400 including the front window frame 298 and roof beams 266 interconnected with the front window frame 298. It should be appreciated that the skeleton 400 could include one or more side window frames, such as the side window frames 324, 338 described above. The roof beam 266 is interconnected to the at least one window frame 298, 324, 338 such that the at least one roof beam 266 and an upper segment of the window frame 298, 324, 338 define at least a portion of the roof frame 296 such that the interconnected roof frame 296, the plurality of posts 234, the panel frame 172, and the floor frame 12 collectively form the skeleton 400 of the building assembly 10.

It should be appreciated that the skeleton 400 is independent of the plurality of panels 84 forming the walls 16 of the building assembly 10. In this way, the panels 84 do not contribute to the structural framework, and the skeleton 400 is solely responsible for the structural integrity of the building assembly 10. The skeleton 400 also provides sufficient clearance between the panels 84 of each wall 16 and the floor 12 and roof 296 frames to allow for expansion and contraction of the panels 84. In an embodiment, at least one of the posts 234 includes the shelf 362 mentioned above. In embodiments where the skeleton 400 includes both side window frames 324, 338, the shelf 362 disposed in the post(s) 234 separates the front 298 and side 324, 338 window frames from the plurality of panels 84 of the walls 16. For example, the shelf 362 serves as a stop for the underlying plurality of panels 84 of adjacent walls 16 to maintain the clearance for the plurality of panels 84 forming the individual walls 16 of the building assembly 10 to allow for the expansion and contraction. By supporting the front 298 and side 324, 338 window frames by the posts 234 (such as by securing the frames 298, 324, 338 to the post 234 with the fasteners 360 described above), the window frames 298, 324, 338, as part of the skeleton 400, remain independent of the underlying panels 84 of the walls 16. This allows the panels 84 to float between the floor frame 12 and the window frames 298, 324, 338. The shelf 362 also serves to prevent the floating panels 84 from pressing against the window frames 298, 324, 338 during expansion of the panels 84.

A method of manufacturing the building assembly 10 is also disclosed. The method includes forming a floor 83. With reference to FIGS. 1-8, the floor 83 is formed by providing the plurality of floor panels 22 each having the first 24 and second 26 ends with the plurality of floor panels 22 including the front floor panel 22_F, the rear floor panel 22_R, and the first 22_{S1} and second 22_{S2} side floor panels. The method of forming the floor 83 further includes mating the first end 24

of one of the plurality of floor panels 22 with the second end 26 of an adjacent one of the plurality of floor panels 22 to interconnect the plurality of floor panels. Mating of the adjacent floor panels 22 may be accomplished by mating one of the upper 40 and lower 42 notches of the one of the plurality of floor panels 22 with the other one of the upper 40 and lower 42 notches of the adjacent one of the plurality of floor panels 22 as previously described. The method of forming the floor 83 further includes attaching the plurality of joists 62, 66 to at least the front 22_F and rear 22_R floor panels to interconnect at least the front 22_F and rear 22_R floor panels and the plurality of joists 62, 66 to form the floor frame 12, and attaching the plurality of interconnected floor boards 80 to the floor frame 12.

The method of manufacturing the building assembly 10 further includes forming the roof 14 spaced from the floor 83 and forming the plurality of walls 16 extending between the floor 83 and the roof 14. Each of the plurality of walls 16 includes the plurality of panels 84 as described in detail above in connection with FIGS. 9-22. The step of forming the plurality of walls 16 includes mating the tongue 118 of one of the plurality of panels 84 with the groove 120 of an adjacent one of the plurality of walls 16, as shown at least in FIGS. 9 and 13-15. Adjacent panels 84 are stacked utilizing the tongue/groove mechanism to form each of the walls 16.

As described in detail above, each of the plurality of panels 84 has the upper notch 106 and the opposing lower notch 108. The method of manufacturing the building assembly 10 further includes mating the lower notch 108 of a first panel 144 of the plurality of panels 84 with the upper notch 106 of a second panel 146 of the plurality of panels 84 to form the interlocking joint 148 between the first 144 and second 146 panels thereby interconnecting the first 144 and second 146 panels and forming adjacent interconnected walls 16 of the plurality of walls 16. The interconnected walls 16 defines the interior 18 and the exterior 20 of the building assembly 10 with at least one of the walls 16 defining the opening 218.

In an embodiment, the first panel 144 is one of a plurality of first panels 144 each having first 86 and second 88 ends and the second panel 146 is one of a plurality of second panels 146 each having first 86 and second 88 ends. The mating step includes mating the lower notch 108 of each of the plurality of first panels 144 about the first end 86 of the first panel 144 with the upper notch 106 of each of the plurality of second panels 146 about the second end 88 of the second panel 146 to form a plurality of first interlocking joints 148 between the plurality of first panels 144 and the plurality of second panels 146 thereby interconnecting the plurality of first panels 144 and the plurality of second panels 146 forming adjacent front 16_F and first side 16_{S1} walls of the plurality of walls 16.

The plurality of panels 84 further includes the plurality of third panels 154 each having first 86 and second 88 ends, and the method further includes the step of mating the lower notch 108 of each of the plurality of third panels 154 about the second 88 of the third panel 154 with the upper notch 106 of each of the plurality of second panels 146 about the first end 86 of the second panel 146 to form a plurality of second interlocking joints 156 between the plurality of second panels 146 and the plurality of third panels 154 thereby interconnecting the plurality of second panels 146 and the plurality of third panels 154 and partially forming the rear wall 16_R adjacent the first side wall 16_{S1} of the building assembly 10.

The plurality of panels 84 further includes the plurality of fourth panels 158 each having first 86 and second 88 ends, and the method further includes the step of mating the lower notch 108 of each of the plurality of third panels 154 about the first end 86 of the third panel 154 with the upper notch 106 of each of the plurality of fourth panels 158 about the second end 88 of the fourth panel 158 to form a plurality of third interlocking joints 160 between the plurality of third panels 154 and the plurality of fourth panels 158 thereby interconnecting the plurality of third panels 154 and the plurality of fourth panels 158 and partially forming the second side wall 16_{S2} adjacent the rear wall 16_R of the building assembly 10.

The method further includes the step of mating the upper notch 106 of each of the plurality of fourth panels 158 about the first end 86 of the fourth panel 158 with the lower notch 108 of each of the plurality of first panels 144 about the second end 88 of the first panel 144 to form a plurality of fourth interlocking joints 162 between the plurality of first panels 144 and the plurality of fourth panels 158 thereby interconnecting the plurality of first panels 144 and the plurality of fourth panels 158.

The step of forming the plurality of walls 16 further includes providing front 130_F and rear 130_R base panels each having a first panel width W_{P1} and attaching the front 130_F and rear 130_R base panels to the front 22_F and rear 22_R floor panels of the floor frame 12, as described above. The method further includes providing the first 130_{S1} and second 130_{S2} base panels each having a second panel width W_{P2} twice the first panel width W_{P1} of the front 130_F and rear 130_R base panels, and attaching the first 130_{S1} and second 130_{S2} side base panels to the first 22_{S1} and second 22_{S2} side floor panels of the floor frame.

The walls 16 of the building assembly 10 may be further formed by attaching the plurality of first panels 144 to the front base panel 130_F to form a front wall 16_F of the plurality of walls 16, attaching the plurality of second panels 146 to the first side base panel 130_{S1} to form a first side wall 16_{S1} of the plurality of walls 16, attaching the plurality of third panels 154 to the rear base panel 130_R to form a rear wall 16_R of the plurality of walls 16, and attaching the plurality of fourth panels 158 to the second side base panel 130_{S2} to form the second side wall 16_{S2} of the plurality of walls 16.

The roof 14 is formed by attaching at least one roof board 366 to the plurality of panels 84 of the plurality of walls 16 of the building assembly 10.

The embodiments of the building assembly 10 described in detail above provide a simplified construction requiring minimal tools for coupling the various components of the building assembly 10 together. The components are formed from lightweight materials for easier handling by the user at least when constructing the building assembly 10. Additionally, various elongated components of the building assembly 10, such as floor panels 22, floor joist 62, wall panels 84, window frame 298, posts 235, panel frames 172, etc., are provided in two parts, enabling all of the components of the building assembly to be easily packaged into a kit. Alternatively, the building assembly 10 could be constructed with elongated components that are formed from a single piece rather than two. The building assembly 10 is a free-standing structure and may be configured to be as large or as small as desired.

The invention has been described in an illustrative manner, and it is to be understood that the terminology which has been used is intended to be in the nature of words of description rather than of limitation. It is now apparent to those skilled in the art that many modifications and varia-

tions of the present invention are possible in light of the above teachings. It is, therefore, to be understood that the invention may be practiced otherwise than as specifically described.

What is claimed is:

1. A building assembly comprising:
a floor frame;
a roof spaced from said floor frame;
a plurality of walls extending between said floor frame and said roof and interconnected to define an interior and an exterior of said building assembly with at least one of said plurality of walls defining an opening and each of said plurality of walls including a plurality of panels with each panel defining a longitudinal axis and each panel having:
first and second ends;
opposing top and bottom surfaces; and
an upper notch formed through said top surface and an opposing lower notch formed through said bottom surface with each of said upper and lower notches spaced inwardly along said longitudinal axis from at least one of said first and second ends,
wherein said plurality of panels includes first and second panels and said lower notch of said first panel mates with said upper notch of said second panel to form an interlocking joint between said first and second panels to interconnect said first and second panels and form adjacent interconnected walls of said plurality of walls of said building assembly; and
a post extending between and coupled to said floor frame and said roof, said post enclosing a space defined by respective portions of said first and second panels extending outwardly from said interlocking joint with said post defining a corner of said exterior of said building assembly, said post further having a slot with said first and second ends of each of said first and second panels extending outwardly from said interlocking joint and received within said slot.

2. The building assembly as set forth in claim 1 wherein said longitudinal axis is further defined as a center axis extending between said first and second ends with said upper notch formed through said top surface and extending toward but terminating prior to said center axis, and said lower notch formed through said bottom surface and extending toward but terminating prior to said center axis.

3. The building assembly as set forth in claim 1 wherein said upper notch has an upper notch depth and said lower notch has a lower notch depth with said upper notch depth the same as said lower notch depth.

4. The building assembly as set forth in claim 1 wherein said upper notch has an upper notch width and said lower notch has a lower notch width with said upper notch width the same as said lower notch width.

5. The building assembly as set forth in claim 1 wherein said upper notch has a first cross-sectional configuration and said lower notch has a second cross-sectional configuration different from said first cross-sectional configuration.

6. The building assembly as set forth in claim 1 wherein each of said plurality of panels has first and second support ribs extending between said first and second ends with said upper notch extending between said top surface and said first support rib and said lower notch extending between said bottom surface and said second support rib.

7. The building assembly as set forth in claim 6 wherein said first support rib is substantially parallel to said top surface and defines a base of said upper notch, and said

second support rib is substantially parallel to said bottom surface and defines a base of said lower notch.

8. The building assembly as set forth in claim 1 wherein said top surface of each of said plurality of panels defines a tongue extending outwardly in a direction transverse to said longitudinal axis and said bottom surface of each of said plurality of panels defines a groove extending inwardly in a direction transverse to said longitudinal axis with said tongue of one of said plurality of panels mating with said groove of an adjacent one of said plurality of panels to form one of said plurality of walls.

9. The building assembly as set forth in claim 1 wherein each panel of said plurality of panels further has opposing inner and outer sides and a mounting channel formed in at least one of said inner and outer sides extending along said longitudinal axis for removably securing an accessory to at least one of said interior and said exterior of said building assembly.

10. The building assembly as set forth in claim 9 wherein said mounting channel is further defined as a first mounting channel formed in said inner side extending along said longitudinal axis for removably securing said accessory to said interior of said building assembly and each panel further has a second mounting channel formed in said outer side extending along said longitudinal axis for removably securing another accessory to said exterior of said building assembly.

11. The building assembly as set forth in claim 10 wherein said first and second mounting channels are spaced a same distance from said top surface such that said first mounting channel is opposite said second mounting channel.

12. The building assembly as set forth in claim 10 wherein said first mounting channel has a first channel depth and said second mounting channel has a second channel depth with said first channel depth the same as said second channel depth, and each of said first and second mounting channels has a stem portion and a chamber portion with said chamber portion having a larger cross-sectional area compared to said stem portion.

13. The building assembly as set forth in claim 10 wherein each of said first and second mounting channels has a P-shaped configuration in cross section.

14. The building assembly as set forth in claim 10 further comprising a plurality of caps coupled to at least one of said first and second ends of each of said plurality of panels with each of said plurality of caps having a head disposed over said at least one of said first and second ends of a respective one of said plurality of panels and each of said plurality of caps having first and second stems each extending from said head with said first stem disposed within said first mounting channel and said second stem disposed within said second mounting channel to mount said cap to said at least one of said first and second ends of said respective one of said plurality of panels.

15. The building assembly as set forth in claim 1 wherein each of said plurality of walls includes a base panel defining a longitudinal axis and having first and second ends, opposing top and bottom surfaces, and an upper notch formed through said top surface spaced inwardly along said longitudinal axis from each of said first and second ends.

16. The building assembly as set forth in claim 15 wherein said plurality of walls includes a front wall, a rear wall opposite said front wall, a first side wall, and a second side wall opposite said first side wall, and said base panel of said front wall and said rear wall having a first panel width and said base panel of said first and second side walls having a second panel width twice the first panel width.

17. The building assembly as set forth in claim 1 wherein said first panel is one of a plurality of first panels each having said first and second ends, said second panel is one of a plurality of second panels each having said first and second ends with said interlocking joint being further defined as a plurality of first interlocking joints each formed between one of said plurality of first panels about said first end of said first panel and one of said plurality of second panels about said second end of said second panel to interconnect said plurality of first panels and said plurality of second panels to partially form adjacent walls of said plurality of walls of said building assembly.

18. The building assembly as set forth in claim 17 wherein said adjacent walls are further defined as front and first side walls, said plurality of panels further includes a third panel and said lower notch of said third panel mates with said upper notch of said second panel to form a second interlocking joint between said second and third panels, and

wherein said third panel is one of a plurality of third panels each having said first and second ends and said second interlocking joint being further defined as a plurality of second interlocking joints each formed between one of said plurality of second panels about said first end of said second panel and one of said plurality of third panels about said second end of said third panel to interconnect said plurality of second panels and said plurality of third panels to partially form a rear wall adjacent said first side wall of said plurality of walls of said building assembly.

19. The building assembly as set forth in claim 18 wherein said plurality of panels further includes a fourth panel and said lower notch of said third panel mates with said upper notch of said fourth panel to form a third interlocking joint between said third and fourth panels, and

wherein said fourth panel is one of a plurality of fourth panels each having said first and second ends and said third interlocking joint being further defined as a plurality of third interlocking joints each formed between one of said plurality of third panels about said first end of said third panel and one of said plurality of fourth panels about said second end of said fourth panel to interconnect said plurality of third panels and said plurality of fourth panels to partially form a second side wall adjacent said rear wall of said plurality of walls of said building assembly.

20. The building assembly as set forth in claim 19 wherein said upper notch of said fourth panel mates with said lower notch of said first panel to form a fourth interlocking joint between said first and fourth panels, and

wherein said fourth interlocking joint is further defined as a plurality of fourth interlocking joints each formed between one of said plurality of fourth panels about said first end of said fourth panel and one of said plurality of first panels about said second end of said first panel to interconnect said plurality of fourth panels and said plurality of first panels.

21. The building assembly as set forth in claim 17 wherein said plurality of panels of each of said adjacent walls has a first section of panels and a second section of panels spaced from said first section of panels,

each panel of said first section of panels has said first end, a first segment end opposite said first end, said upper notch formed through said top surface, and said opposing lower notch formed through said bottom surface with said upper and lower notches spaced inwardly along said longitudinal axis from said first end, and

each panel of said second section of panels has said second end, a second segment end opposite said second end, said upper notch formed through said top surface, and said opposing lower notch formed through said bottom surface with said upper and lower notches spaced inwardly along said longitudinal axis from said second end, and

further comprising a panel frame disposed between said first and second sections of panels with said panel frame connected to said first segment end of each of said first section of panels and connected to said second segment end of each of said second section of panels to interconnect said first and second sections of panels of said first side wall.

22. The building assembly as set forth in claim 21 wherein said panel frame has first and second frame segments each defining a slot, and said panel frame further has a tab extending from one of said first and second frame segments and coupled to another one of said first and second frame segments to interconnect said first and second frame segments and form said panel frame of said first side wall.

23. The building assembly as set forth in claim 21 wherein said panel frame has an upper side, a lower side opposite said upper side, a first side, and a second side opposite said first side with said upper side, lower side, first side, and second side interconnected to define an opening for providing access to an inside of said building assembly.

24. The building assembly as set forth in claim 1 wherein said post has first and second post segments and said post further having a tab extending from one of said first and second post segments and coupled to another one of said first and second post segments to interconnect said first and second post segments and form said post at said corner of said exterior of said building assembly.

25. The building assembly as set forth in claim 1 wherein said first panel is one of a plurality of first panels and said second panel is one of a plurality of second panels and said plurality of walls includes:

a front wall formed from said plurality of first panels and a front window frame supported by said plurality of first panels with said front window frame having first and second side segments and a front window bracket extending from at least one of said first and second side segments with said front window bracket having upper and lower surfaces and a slot defined through said lower surface;

a first side wall adjacent said front wall and formed from said plurality of second panels and a side window frame supported by said plurality of second panels with said side window frame having first and second side segments and a side window bracket extending from at least one of said first and second side segments with said side window bracket having upper and lower surfaces and a slot defined through said upper surface, wherein said slot of said front window bracket mates with said slot of said side window bracket to interconnect said front and side window frames to partially interconnect said front and side walls.

26. The building assembly as set forth in claim 25, wherein said post extends adjacent to said front and first side walls with said post having first and second post sides with said front window bracket adjacent said first post side and said side window bracket adjacent said second post side, and wherein said building assembly further comprises:

a plurality of fasteners with one of said fasteners securing said front window bracket to said first post side and

another one of said fasteners securing said side window bracket to said second post side.

27. The building assembly as set forth in claim 25, wherein said post is adjacent to said front and first side walls with said post having a shelf separating said front and side window frames from said plurality of panels.

28. The building assembly as set forth in claim 1 wherein said plurality of walls includes a front wall and said plurality of panels forming said front wall has a first section of panels and a second section of panels spaced from said first section of panels, with each panel of said first section of panels having a first end and a first segment end opposite said first end and each panel of said second section of panels having a second end and a second segment end opposite said second end, and further comprising:

a door frame disposed between said first and second sections of panels with said door frame having an upper side, a lower side, a first side, and a second side with each of said upper, lower, first, and second sides defining a channel, with said first segment end of each panel of said first section of panels received within said channel of said first side of said door frame and secured to said first side of said door frame and said second segment end of each panel of said second section of panels received within said channel of said second side of said door frame and secured to said second side of said door frame; and

a front window frame having top and bottom segments with said bottom segment of said window frame coupled to said upper side of said door frame such that said door frame partially supports said front window frame.

29. The building assembly as set forth in claim 1 wherein said roof includes a plurality of interconnected roof beams coupled to said plurality of panels of each of said plurality of walls, and said roof further including at least one roof board secured to said plurality of interconnected roof beams.

30. The building assembly as set forth in claim 29 wherein said at least one roof board is further defined as a plurality of front roof boards and a plurality of rear roof boards adjacent said plurality of front roof boards, with each one of said plurality of front roof boards having front and back sides and a flange extending from said back side and overlapping a respective one of said plurality of rear roof boards to form a first seal between said plurality of front roof boards and said plurality of rear roof boards.

31. The building assembly as set forth in claim 30 wherein said plurality of front roof boards has a plurality of interconnected sheets of material including a top sheet, a bottom sheet, and at least one middle sheet, and each one of said plurality of rear roof boards has front and back sides and at least one flange extending from said front side of said rear roof board with said at least one middle sheet of said plurality of front roof boards overlapping said flange of said rear roof board to form a second seal between said plurality of front roof boards and said plurality of rear roof boards.

32. The building assembly as set forth in claim 1 wherein said floor frame comprises a plurality of floor panels with one of said plurality of floor panels mating with an adjacent one of said plurality of floor panels to interconnect said plurality of floor panels and form said floor frame, and

wherein said plurality of floor panels includes a front floor panel, a rear floor panel spaced from said front floor panel, a first side floor panel extending between said front and rear floor panels, and a second side floor panel extending between said front and rear floor panels and spaced from said first side floor panel.

33. The building assembly as set forth in claim 32 wherein each of said plurality of floor panels has first and second floor panel segments each defining a slot, and one of said first and second floor panel segments having a tab disposed within said slot of the other one of said first and second floor panel segments to interconnect said first and second floor panel segments to form said floor panel.

34. The building assembly as set forth in claim 32 wherein said floor frame further has a first floor joist extending between said first and second side floor panels, a plurality of second floor joists extending between said front floor panel and said first floor joist, and another plurality of second floor joists extending between said first floor joist and said rear floor panel.

35. The building assembly as set forth in claim 34 wherein each of said plurality of floor panels has a ledge and further comprising at least one floor board supported by said first floor joist, said plurality of second floor joists, and said ledges to form a floor of said building assembly.

36. The building assembly as set forth in claim 1 further comprising a door coupled to said at least one of said plurality of walls and movable between an open position in which said door is spaced from said opening and a closed position in which said door covers said opening.

37. A method of manufacturing a building assembly comprising the steps of:

forming a floor;
forming a roof spaced from the floor;
forming a plurality of walls extending between the floor and the roof with each of the plurality of walls including a plurality of panels with each panel defining a longitudinal axis and each panel having first and second ends, opposing inner and outer sides, opposing top and bottom surfaces, an upper notch formed through the top surface and an opposing lower notch formed through the bottom surface with each of the upper and lower notches spaced inwardly along the longitudinal axis from at least one of the first and second ends, a first mounting channel formed in the inner side extending along the longitudinal axis, and a second mounting channel formed in the outer side extending along the longitudinal axis, with the plurality of panels including first and second panels;

mating the lower notch of the first panel with the upper notch of the second panel to form an interlocking joint between the first and second panels thereby interconnecting the first and second panels and forming adjacent interconnected walls of the plurality of walls, wherein the first and second ends of the first and second panels extend outwardly from said interlocking joint, and wherein said interconnected plurality of walls defines an interior and an exterior of the building assembly with at least one of the plurality of walls defining an opening;

coupling a post between the floor frame and the roof with the post having a slot and with the first and second ends of the first and second panels received within the slot; and

coupling a door to at least one of the plurality of walls such that the door is movable between an open position in which the door is spaced from the opening and a closed position in which the door covers the opening.

38. The method as set forth in claim 37 wherein the top surface of each of the plurality of panels defines a tongue extending outwardly in a direction transverse to the longitudinal axis and the bottom surface of each of the plurality of panels defines a groove extending inwardly in a direction

31

transverse to the longitudinal axis and further comprising the step of mating the tongue of one of the plurality of panels with the groove of an adjacent one of the plurality of panels to form one of the plurality of walls.

39. The method as set forth in claim 37 wherein the first panel is one of a plurality of first panels each having first and second ends and the second panel is one of a plurality of second panels each having first and second ends and the mating step includes mating the lower notch of each of the plurality of first panels about the first end of the first panel with the upper notch of each of the plurality of second panels about the second end of the second panel to form a plurality of first interlocking joints between the plurality of first panels and the plurality of second panels thereby interconnecting the plurality of first panels and the plurality of second panels and partially forming adjacent front and side walls of the plurality of walls.

40. The method as set forth in claim 39 wherein the plurality of panels further includes a plurality of third panels each having first and second ends and further comprising the step of mating the lower notch of each of the plurality of third panels about the second end of the third panel with the upper notch of each of the plurality of second panels about the first end of the second panel thereby interconnecting the plurality of second panels and the plurality of third panels and partially forming a rear wall adjacent the first side wall of the building assembly.

41. The method as set forth in claim 40 wherein the plurality of panels further includes a plurality of fourth panels each having first and second ends and further comprising the step of mating the lower notch of each of the plurality of third panels about the first end of the third panel with the upper notch of each of the plurality of fourth panels about the second end of the fourth panel thereby interconnecting the plurality of third panels and the plurality of fourth panels and partially forming a second side wall adjacent the rear wall of the building assembly.

42. The method as set forth in claim 41 further comprising the step of mating the upper notch of each of the plurality of fourth panels about the first end of the fourth panel with the lower notch of each of the plurality of first panels about the second end of the first panel to form a plurality of fourth interlocking joints between the plurality of first panels and the plurality of fourth panels thereby interconnecting the plurality of first panels and the plurality of fourth panels.

43. The method as set forth in claim 37 wherein the step of forming the floor includes the steps of:

providing a plurality of floor panels each having first and second ends with the plurality of floor panels including a front floor panel, a rear floor panel, and first and second side floor panels;

mating the first end of one of the plurality of floor panels with the second end of an adjacent one of the plurality of floor panels to interconnect the plurality of floor panels;

attaching at least one joist to said plurality of floor panels to interconnect said plurality of floor panels and said at least one joist to form a floor frame; and

attaching a plurality of interconnected floor boards to the floor frame.

44. The method as set forth in claim 43 wherein the plurality of walls includes a front wall, a rear wall spaced from the front wall, a first side wall extending between the front and rear walls, and a second side wall spaced from the first side wall and extending between the front and rear walls and the step of forming the plurality of walls includes:

32

providing front and rear base panels each defining a longitudinal axis and having first and second ends, opposing top and bottom surfaces, an upper notch formed through the top surface spaced inwardly along the longitudinal axis from each of the first and second ends, and a first panel width;

attaching the front and rear base panels to the front and rear floor panels of the frame;

providing first and second side base panels each defining a longitudinal axis and having first and second ends, opposing top and bottom surfaces, an upper notch formed through the top surface spaced inwardly along the longitudinal axis from each of the first and second ends, a lower notch formed through the bottom surface spaced inwardly along the longitudinal axis from each of the first and second ends, and a second panel width twice the first panel width of the front and rear base panels; and

attaching the first and second side base panels to the first and second side floor panels of the frame.

45. The method as set forth in claim 44 wherein the first panel is one of a plurality of first panels, the second panel is one of a plurality of second panels, and the plurality of panels further includes a plurality of third panels and a plurality of fourth panels and further comprising the steps of:

attaching the plurality of first panels to the front base panel to form a front wall of the plurality of walls;

attaching the plurality of second panels to the first side base panel to form a first side wall of the plurality of walls;

attaching the plurality of third panels to the rear base panel to form a rear wall of the plurality of walls; and attaching the plurality of fourth panels to the second side base panel to form a second side wall of the plurality of walls.

46. A building assembly comprising:

a floor frame;

a roof spaced from said floor frame;

a plurality of walls extending between said floor frame and said roof and interconnected to define an interior and an exterior of said building assembly with at least one of said plurality of walls defining an opening and each of said plurality of walls including a plurality of panels with each panel defining a longitudinal axis and each panel having:

first and second ends;

opposing top and bottom surfaces; and

an upper notch formed through said top surface and an opposing lower notch formed through said bottom surface with each of said upper and lower notches spaced inwardly along said longitudinal axis from at least one of said first and second ends,

wherein said plurality of panels includes first and second panels and said lower notch of said first panel mates with said upper notch of said second panel to form an interlocking joint between said first and second panels to interconnect said first and second panels and form adjacent interconnected walls of said plurality of walls of said building assembly, wherein each panel of said plurality of panels further

has opposing inner and outer sides and a mounting channel formed in at least one of said inner and outer sides extending along said longitudinal axis for removably securing an accessory to at least one of said interior and said exterior of said building assembly,

wherein said mounting channel is further defined as a first mounting channel formed in said inner side extending along said longitudinal axis for removably securing said accessory to said interior of said building assembly and each panel further has a second mounting channel formed in said outer side extending along said longitudinal axis for removably securing another accessory to said exterior of said building assembly, and

a plurality of caps coupled to at least one of said first and second ends of each of said plurality of panels with each of said plurality of caps having a head disposed over said at least one of said first and second ends of a respective one of said plurality of panels and each of said plurality of caps having first and second stems each extending from said head with said first stem disposed within said first mounting channel and said second stem disposed within said second mounting channel to mount said cap to said at least one of said first and second ends of said respective one of said plurality of panels.

47. A building assembly comprising:

a floor frame;

a roof spaced from said floor frame; and

a plurality of walls extending between said floor frame and said roof and interconnected to define an interior and an exterior of said building assembly with at least one of said plurality of walls defining an opening and each of said plurality of walls including a plurality of panels with each panel defining a longitudinal axis and each panel having:

first and second ends;

opposing top and bottom surfaces; and

an upper notch formed through said top surface and an opposing lower notch formed through said bottom surface with each of said upper and lower notches spaced inwardly along said longitudinal axis from at least one of said first and second ends,

wherein said plurality of panels includes first and second panels and said lower notch of said first panel mates with said upper notch of said second panel to form an interlocking joint between said first and second panels to interconnect said first and second panels and form adjacent interconnected walls of

said plurality of walls of said building assembly, wherein said first panel is one of a plurality of first panels and said second panel is one of a plurality of second panels and said plurality of walls includes: a front wall formed from said plurality of first panels and a front window frame supported by said plurality of first panels with said front window frame having first and second side segments and a front window bracket extending from at least one of said first and second side segments with said front window bracket having upper and lower surfaces and a slot defined through said lower surface;

a first side wall adjacent said front wall and formed from said plurality of second panels and a side window frame supported by said plurality of second panels with said side window frame having first and second side segments and a side window bracket extending from at least one of said first and second side segments with said side window bracket having upper and lower surfaces and a slot defined through said upper surface,

wherein said slot of said front window bracket mates with said slot of said side window bracket to interconnect said front and side window frames to partially interconnect said front and side walls.

48. The building assembly as set forth in claim 47, wherein said building assembly further comprises:

a post extending between said floor frame and said roof and adjacent said front and first side walls with said post having first and second post sides with said front window bracket adjacent said first post side and said side window bracket adjacent said second post side; and

a plurality of fasteners with one of said fasteners securing said front window bracket to said first post side and another one of said fasteners securing said side window bracket to said second post side.

49. The building assembly as set forth in claim 47, further comprising a post extending between said floor frame and said roof adjacent to said front and first side walls with said post having a shelf separating said front and side window frames from said plurality of panels.
